Application July 19, 1945, Serial No. 605,952

12 Claims. (Cl. 260—683.4)

1

This application is a continuation-in-part of our copending application Serial No. 439,816, filed April 12, 1942, and now abandoned.

This invention relates to the catalytic manufacture of high octane gasoline. The invention is directed particularly to a method of catalytically reforming a relatively narrow boiling isoparaffin fraction, such as, for example, a typical paraffinic alkylate, so as to give a complete gasoline of high octane value.

The alkylation of isoparaffinic hydrocarbons with olefinic hydrocarbons for the production of isoparaffins of high octane value boiling in the gasoline range is now a well established art. Heretofore, various catalysts have been proposed for this reaction, such as sulfuric acid, phosphoric acid, aluminum chloride, etc. It has more recently been discovered in U. S. Patent No. 2,267,730 that alkylation reactions of the above type may be carried out in a highly desirable manner by using a catalyst consisting essentially of hydrogen fluoride.

Since alkylation processes, as usually conducted, effect predominantly the condensation of one particular isoparaffin with one particular olefin, the resulting alkylate gasoline, although of high octane value, is composed predominantly of isomers of one paraffinic hydrocarbon. Therefore, the alkylate is of relatively narrow boiling range which is less than that of a complete gasoline, or, at least, such alkylate does not have a uniform distribution of hydrocarbons across the desired gasoline boiling range. As is well known, gasolines should be of adequate boiling range and have their constituents rather uniformly distributed in order to insure proper carburetion and combustion. For this reason, expensive alkylate gasoline is now blended with gasoline of inferior anti-knock value in order to obtain a blended gasoline of proper distillation characteristics and vapor pressure.

In Patent Number 2,403,929, July 16, 1946, there is disclosed that hydrogen fluoride will effect a catalytic re-arrangement or reforming of isoparaffins, such as alkylate hydrocarbons, boiling in the gasoline range to yield a composite gasoline which boils over an entire gasoline range and which possesses substantially as high an anti-knock value as a blended alkylate gasoline. In accordance with that invention, there is shown, for example, a process of reforming isoparaffins in the presence of hydrogen fluoride to yield a hydrocarbon mixture which boils over an entire gasoline range. It is especially interesting to note that this process is capable of effecting such a complete conversion or reaction of the hydro-

2

carbons that lower boiling hydrocarbons may be formed from the charge stock, as well as higher boiling hydrocarbons. The present invention is directed particularly to a specific method for carrying out the reforming process disclosed in such patent, although more broadly, the invention is directed to a novel manner of separating and handling the constituents of a hydrocarbon-hydrogen fluoride reaction mixture.

10 It is an object of this invention to provide a highly efficient procedure for separating and handling portions of a hydrocarbon reaction mixture which has been produced in the presence of and which contains a hydrogen fluoride catalyst. A more specific object is to provide an improved method of catalytically reforming a narrow boiling fraction of gasoline boiling isoparaffins, as, for example, a butane-butylene or butane-propylene alkylate, in the presence of hydrogen fluoride. A still more specific object is to catalytically reform such narrow boiling fractions by a novel method to obtain a complete gasoline of high octane value and proper vapor pressure and distillation characteristics.

25 Accordingly, an embodiment of our invention is carried out by feeding an entire alkylation reaction mixture containing hydrofluoric acid catalyst into a fractionating unit, and in this unit the isoparaffins are reformed by further contact with the hydrogen fluoride catalyst under conditions which maintain material of gasoline-boiling range and higher in liquid form while lighter material, including hydrogen fluoride, vaporizes. These vapors of lighter material are led to a condenser, and the condensate therefrom is allowed to separate into two layers, viz., an upper hydrocarbon layer and a lower hydrogen fluoride layer. The hydrocarbon layer is composed primarily of light isoparaffins, e.g., isobutane and isopentane, which are left over from the charge stock, if present therein, and which are produced during the reforming step. The normally liquid hydrocarbons of the reaction mixture and some hydrogen fluoride are withdrawn from the fractionating unit in liquid form and treated in a manner later described.

30 For a fuller understanding of the invention, reference will be made to the accompanying drawings, wherein Figure 1 shows diagrammatically a preferred apparatus setup for conducting our process, and Figure 2 is a graph showing the ability of our reforming process to produce new products of vastly different distillation characteristics from narrow boiling fractions of gasoline boiling isoparaffins.

35 In operation—referring now to Figure 1—a

suitable isoparaffinic charging stock is fed continuously through lines 1 and 2 onto a feed plate 3, in the middle of column 4. Column 4 may perform the dual function of a fractionation and a reforming chamber, and is suitably constructed for effecting proper contact of isoparaffins and HF. Lower boiling liquid isoparaffins are used as a reflux for column 4, and are introduced by line 5 to distributor 6. In order to afford still greater flexibility of operation in column 4, provision is made for introducing liquid HF through line 7 to column 4 at a point below where reaction mixture is fed in. This serves to increase the quantity of HF in contact with the high boiling hydrocarbons and, therefore, the extent of reforming—all other factors being constant. Provision for returning additional liquid HF to the bottom section of the column can be made by recycling a part of the HF from gravity separator 8.

Conditions within the column 4 are maintained so that gasoline boiling hydrocarbons and higher boiling hydrocarbons remain liquid and are drawn off at the bottom of the column through pipe 17. Lighter hydrocarbon material and a portion of the hydrogen fluoride vaporize and the resulting vapors pass upwardly through the column counter-current to the down-flowing liquid. These vapors are led from the top of column 4 through line 9 to condenser 10. The condensate from condenser 10 is led through line 11 and line 12 to gravity separator 13, and a part also may be recycled through line 11 and line 14 to reaction vessel 15, containing high-speed mixer 15a. The condensate in separator 13 separates into two layers, namely, an upper hydrocarbon layer and a lower hydrogen fluoride layer. The upper hydrocarbon layer in separator 13 passes through line 5 to column 4 as reflux, and the lower hydrogen fluoride layer in separator 13 passes through line 7 to the bottom of column 4, both as explained hereinabove. If desired, however, any part of either of the two layers in separator 13 might be sent to reactor 15 by suitable pipes (not shown). Additional hydrogen fluoride as needed may be introduced to the system through line 16.

The crude reformed product is withdrawn from the bottom of column 4 through line 17 and passed into gravity separator 8. Here the product separates from accompanying liquid HF to form two layers. The product layer is taken through line 18 to fractionating and/or refining equipment (not shown). The HF in separator 8 is removed through line 19 and passed thereby back to reaction vessel 15, or it is diverted from line 19 through line 20 and sent either through line 21 back to the bottom of column 4 or sent through line 22 to an HF purification system (not shown) and the purified HF is returned to the system. This purification system may comprise merely a distillation column for vaporizing HF.

The liquid product withdrawn from the bottom of column 4 and sent to the fractionation system may be fractionated in order to cut out a desired gasoline fraction, and the light and heavy ends obtained in this fractionation, may be led either to reactor 15, along with the low boiling isoparaffins (isobutane and isopentane) taken over-head in column 4, for further treatment in the presence of HF, or may be withdrawn permanently from the reaction cycle. It is usually desirable, however, to return the heavy ends to the reaction vessel 15 along with low boiling isoparaffins and HF, in order to increase the yield of gasoline-boiling hydrocarbons. This may be done by means of line 23. These heavy ends behave like olefins in reacting with light isopar-

affins, and, therefore, are an additional source of isoparaffinic charging stock for column 4, as well as other gasoline-boiling hydrocarbons. Since the temperature and other conditions for reacting the heavy ends with light isoparaffins in reactor 15 are essentially the same as HF alkylation conditions, this reactor may also be used to react light isoparaffins with olefins by simply introducing suitable amounts of olefins along with the heavy ends, as, for example, through line 23. Reaction mixture withdrawn from reactor 15 is sent to column 4 via lines 25 and 2.

Therefore, it may be seen that the isoparaffinic material of gasoline boiling range which is sent to column 4 may be derived from several sources. Thus, the isoparaffinic charge stock fed through line 1 may be isoparaffins of gasoline boiling range derived from any source, and, of course, might be the reaction mixture of an HF alkylation process. In this latter case, such HF alkylation process may be conducted in a separate reactor or it may be conducted in the reactor 15 along with the other reactions mentioned above as being carried out in reactor 15. In any of these embodiments, all, any part or none of the materials mentioned above as being recycled to reactor 15 may be so recycled.

Column 4, as explained hereinabove, is preferably both a reforming and fractionating unit and is of appropriate construction therefor. Thus, for example, the section of the column above the feed plate 3 may comprise a series of bubble-cap trays which serve to strip the low boiling hydrocarbons from the higher boiling hydrocarbons; while the section below this feed plate may be packed with an inert material, as, for example, carborundum, with occasional bubble-cap trays being used as collectors and re-distributors of liquids. It is to be understood that the single column 4 could be replaced by two columns, one of which performs the function of the upper section of column 4 while the other performs the function of the lower section of column 4. Moreover, if desired, the alkylation reactor might be made a section of the column.

The higher boiling hydrocarbons which travel downwardly through the lower section of the column in the presence of the liquid HF are reformed to an extent which is dependent upon: (1) contact time, (2) temperature, (3) ratio of low boiling (usually isobutane) to high boiling hydrocarbons in the mixture, and (4) amount of HF present. These four variables may be adjusted to give substantially any gasoline range material desired. It is a simple matter to substantially completely alter the hydrocarbons of the narrow boiling range charging stock to give a mixture of hydrocarbons which form a complete high octane gasoline of proper distillation and vapor pressure characteristics.

The advantages and improvements effected by a reforming operation of the type brought about in fractionating-reforming column 4 of our apparatus are best shown, perhaps, by the graph in Figure 2. In this graph per cent volume of gasoline distilled is plotted against distillation temperature, and three curves are given, viz., curves A, B, and C. By referring to this graph, it will be seen that a heptane alkylate, produced by alkylating isobutane with propylene and represented by curve A, is concentrated in a rather narrow boiling range between 80 and 100° C. On the other hand, curve B shows that when this heptane alkylate is reformed (in the absence of added hydrocarbons), a mixture of hydrocarbons is obtained which distills rather uniformly

over an entire gasoline range. It also should be noted that the reformed product is essentially a totally different product from the original alkylate. Thus, only about 10 to 12% of the reformed product boils within the boiling range of the entire alkylate fraction. Moreover, even the 10 to 12% of hydrocarbons remaining in this same range need not necessarily be of the same structure as the original alkylate hydrocarbons. Curve C shows that when added isobutane is present, modification of the final product is obtained which still yields a gasoline boiling rather uniformly over the entire gasoline range but having a higher concentration of hydrocarbons in the middle portion of the gasoline. This concentration of hydrocarbons in the middle portion of the gasoline can be varied to almost any extent by the present invention which removes the light hydrocarbon gases from the alkylate prior to separation of HF from the alkylate. This effect of the isobutane apparently is one of mass action.

The temperature for reforming isoparaffins in the presence of HF may be between, say about -10 and about 200° C., depending upon the desired operating pressure and the reactivity of the isoparaffins. Providing sufficient contact time in the column to attain the desired amount of reforming, presents no particular problem. The effect obtained by varying the amount of light gaseous hydrocarbons and also hydrofluoric acid has been described above, as well as means for attaining same. Therefore, it should be apparent that the variables of the process are subject to complete control, and may be easily correlated to give the desired result.

An outstanding feature of our process resides in the fact that light gaseous ends are removed from the reaction mixture in the presence of an excess of HF, and by means of HF, and before the remainder of the hydrocarbons are separated from HF. As a result, we are able to exert a greater influence on the reforming step and regulate to a finer degree the characteristics of the product. Thus, in most cases, it is desirable to have the isoparaffinic charging stock free of low boiling isoparaffins, including even the small amount produced during reforming, before separating the product from HF. This, of course, is accomplished easily by the present process.

It is perhaps well to note at this time that the distillation of two immiscible liquids, such as a mixture of liquid HF and liquid hydrocarbons, follows a "steam distillation" principle according to the equation:

$$\frac{W_{HF}}{W_{HC}} = \frac{P_{HF}M_{HF}}{P_{HC}M_{HC}}$$

where:

W_{HF} =weight of HF in overhead vapors

W_{HC} =weight of hydrocarbon in overhead vapors

P_{HF} =vapor pressure of HF at temperature t

P_{HC} =vapor pressure of hydrocarbon at temperature t

M_{HF} =molecular weight of HF in vapor phase at temperature t

M_{HC} =molecular weight of hydrocarbon vapor at temperature t .

However, HF is highly associated in the vapor phase and its apparent molecular weight varies from about 77 at -10° C. to about 25 at 130° C. It will be seen, therefore, that W_{HF}/W_{HC} decreases with increasing temperature. Accordingly, it follows that a more complete separation of HF from isobutane by distillation can be obtained

at higher temperatures. Therefore, if desired, the operation in column 4 may be conducted at temperatures which are substantially above the boiling point of hydrogen fluoride at atmospheric pressure (which is 19.4° C.) both because of the above reason and also because a higher reforming temperature is thereby maintained.

The amount of HF charged to the column in excess of that leaving the column as overhead vapor in combination with isobutane will be liquid and in admixture with the higher boiling hydrocarbons in the bottom of the column, and this amount of liquid HF can be augmented by additional recycle HF as described hereinabove. Concentrated hydrofluoric acid between about 90 and 100% concentration is capable of serving as our catalyst. Use of the essentially anhydrous hydrogen fluoride is attractive because the separation of water or dilute hydrofluoric acid in the distillation step involved in our reforming operation is eliminated. However, it is to be noted that 95 to 99% acid is an alkylating agent of higher specificity and may be used.

The process described above is also described in our co-pending application Serial No. 439,816, filed April 12, 1942 and now abandoned.

We claim:

1. The process of producing a relatively wide boiling mixture of high quality gasoline boiling hydrocarbons from a relatively narrow boiling alkylate produced by an alkylation step wherein light iso-paraffins are reacted with olefins under alkylation conditions in the presence of a catalyst consisting essentially of hydrogen fluoride, which comprises passing alkylation reaction mixture comprising relatively narrow boiling alkylate gasoline, normally gaseous hydrocarbons, and hydrogen fluoride to a fractionating-reforming zone, maintaining said zone under such conditions that normally gaseous hydrocarbons are vaporized while gasoline boiling hydrocarbons and higher hydrocarbons remain in the liquid state, continuing to contact said alkylate with said hydrogen fluoride in said fractionating-reforming zone until substantial reforming of the alkylate is effected, fractionating off the normally gaseous hydrocarbons from said zone during the reforming operation as a vapor mixture with hydrogen fluoride, withdrawing a mixture of reformed gasoline boiling hydrocarbons, higher hydrocarbons and hydrogen fluoride in liquid phase from near the bottom of said zone, condensing said vapor mixture and separating the condensate into a hydrocarbon layer and a hydrogen fluoride layer, passing the hydrocarbon layer to the top of said fractionation zone as reflux and passing the hydrogen fluoride layer to said zone at a point near the bottom thereof, separating said withdrawn liquid mixture into a hydrocarbon phase and a hydrogen fluoride phase, fractionating said hydrocarbon phase to produce a gasoline boiling fraction and a fraction of higher boiling liquid hydrocarbons and returning this latter fraction to the alkylation step.

2. The process of claim 1, wherein the contact between the hydrogen fluoride and the normally liquid hydrocarbons in said fractionating-reforming zone is sufficient to produce a complete gasoline of proper distillation and vapor pressure characteristics.

3. The process of producing high quality gasoline from a relatively narrow boiling alkylate produced by an alkylation step wherein light iso-paraffins are reacted with olefins under alkylat-

ing conditions in the presence of a catalyst consisting essentially of hydrogen fluoride, which comprises passing alkylation reaction mixture comprising relatively narrow boiling alkylate gasoline, normally gaseous hydrocarbons, and hydrogen fluoride to a fractionating-reforming zone, maintaining said zone under such conditions that normally gaseous hydrocarbons are vaporized while gasoline boiling hydrocarbons and higher hydrocarbons remain in the liquid state, continuing to contact said alkylate with said hydrogen fluoride in said fractionating-reforming zone until sufficient reforming of the alkylate is effected, to give a complete gasoline of proper distillation and vapor pressure characteristics, fractionating off the normally gaseous hydrocarbons from said zone during the reforming operation as a vapor mixture with hydrogen fluoride, withdrawing reformed gasoline and higher hydrocarbons in liquid phase from said zone, fractionating said withdrawn gasoline and higher hydrocarbons to give a gasoline fraction and a fraction of higher liquid hydrocarbons, and returning said fraction of higher hydrocarbons to said alkylation step for the production of further quantities of gasoline boiling hydrocarbons.

4. The process of producing a relatively wide boiling mixture of high quality gasoline boiling hydrocarbons from a relatively narrow boiling alkylate produced by an alkylation step wherein light isoparaffins are reacted with olefins under alkylating conditions in the presence of a catalyst consisting essentially of hydrogen fluoride, which comprises passing alkylation reaction mixture comprising relatively narrow boiling alkylate gasoline, normally gaseous hydrocarbons, and hydrogen fluoride to a fractionating-reforming zone, maintaining said zone under such conditions that normally gaseous hydrocarbons are vaporized while gasoline boiling hydrocarbons and higher hydrocarbons remain in the liquid state, continuing to contact said alkylate with said hydrogen fluoride in said fractionating-reforming zone until substantial reforming of the alkylate is effected, fractionating off the normally gaseous hydrocarbons from said zone during the reforming operation as a vapor mixture with hydrogen fluoride, withdrawing reformed gasoline boiling hydrocarbons and higher hydrocarbons in liquid phase from said zone, fractionating said withdrawn liquid hydrocarbons to give a gasoline boiling fraction and a fraction of higher liquid hydrocarbons, and returning said fraction of higher liquid hydrocarbons to said alkylation step for the production of further quantities of gasoline boiling hydrocarbons.

5. The process of manufacturing high quality gasoline from a relatively narrow boiling alkylate produced by reacting light isoparaffins with olefins in the presence of a catalyst consisting essentially of hydrogen fluoride, which comprises passing alkylation reaction mixture comprising relatively narrow boiling alkylate gasoline, normally gaseous hydrocarbons, and hydrogen fluoride to a fractionating-reforming zone, maintaining said zone under such conditions that normally gaseous hydrocarbons are vaporized while gasoline boiling hydrocarbons and higher hydrocarbons remain in the liquid state, continuing to contact said alkylate with said hydrogen fluoride in said fractionating-reforming zone until sufficient reforming of the alkylate is effected to give a complete high quality gasoline of proper distillation and vapor pressure

characteristics, fractionating off the normally gaseous hydrocarbons from said zone during the reforming operation as a vapor mixture with hydrogen fluoride, and withdrawing said high quality gasoline and higher hydrocarbons in liquid phase from said zone.

6. The process of producing a relatively wide boiling mixture of high quality gasoline boiling hydrocarbons from a relatively narrow boiling alkylate produced by reacting light isoparaffins with olefins in the presence of a catalyst consisting essentially of hydrogen fluoride, which comprises passing alkylation reaction mixture comprising relatively narrow boiling alkylate gasoline, normally gaseous hydrocarbons, and hydrogen fluoride to a fractionating-reforming zone, maintaining said zone under such conditions that normally gaseous hydrocarbons are vaporized while gasoline boiling hydrocarbons and higher hydrocarbons remain in the liquid state, continuing to contact said alkylate with said hydrogen fluoride in said fractionating-reforming zone until substantial reforming of the alkylate is effected, fractionating off the normally gaseous hydrocarbons from said zone during the reforming operation as a vapor mixture with hydrogen fluoride, withdrawing gasoline boiling hydrocarbons and higher hydrocarbons in liquid phase from near the bottom of said zone.

7. The process of claim 6, wherein the distilling off of the vapor mixture of hydrogen fluoride and normally gaseous hydrocarbons from the fractionation zone is effected by distilling at a temperature which is substantially above the atmospheric boiling point of hydrogen fluoride so as to obtain a relatively low ratio of hydrogen fluoride to hydrocarbons in said vapor mixture.

8. The process of producing a relatively wide boiling mixture of high quality gasoline boiling hydrocarbons from a relatively narrow boiling alkylate produced by reacting light isoparaffins with olefins in the presence of a catalyst consisting essentially of hydrogen fluoride, which comprises passing alkylation reaction mixture comprising relatively narrow boiling alkylate gasoline, normally gaseous hydrocarbons, and hydrogen fluoride to a fractionating-reforming zone, maintaining said zone under such conditions that normally gaseous hydrocarbons are vaporized while gasoline boiling hydrocarbons and higher hydrocarbons remain in the liquid state, continuing to contact said alkylate with said hydrogen fluoride in said fractionating-reforming zone until substantial reforming of the alkylate is effected, fractionating off the normally gaseous hydrocarbons from said zone during the reforming operation as a vapor mixture with hydrogen fluoride, withdrawing reformed gasoline boiling hydrocarbons, heavier hydrocarbons and hydrogen fluoride in liquid phase from said zone, and recycling said normally gaseous hydrocarbons and said heavier hydrocarbons removed from said fractionating-reforming zone to said alkylation step.

9. The process of producing reformed gasoline of relatively wide boiling range from a relatively narrow boiling fraction of gasoline boiling isoparaffins which comprises feeding the relatively narrow boiling fraction of isoparaffins and a catalyst consisting of hydrofluoric acid as the effective catalytic agent to a fractionating-reforming zone, maintaining said zone under such conditions that normally gaseous hydrocarbons are vaporized while gasoline boiling hydrocarbons and higher hydrocarbons remain in the liquid state, contacting said isoparaffins with said hydrogen

fluoride in said fractionating-reforming zone until sufficient reforming of isoparaffins is effected to give complete gasoline of proper distillation and vapor pressure characteristics, fractionating off normally gaseous hydrocarbons from said zone during the reforming operation as a vapor mixture with hydrogen fluoride, condensing and returning at least a portion of the vaporized hydrogen fluoride to said zone, and withdrawing said complete reformed gasoline and higher boiling hydrocarbons in liquid phase from said zone.

10. The process of producing reformed gasoline of relatively wide boiling range from a relatively narrow boiling fraction of gasoline boiling isoparaffins which comprises feeding the relatively narrow boiling fraction of isoparaffins and a catalyst consisting of hydrofluoric acid as the effective catalytic agent to a fractionating-reforming zone, maintaining said zone under such conditions that normally gaseous hydrocarbons are vaporized while gasoline boiling hydrocarbons and higher hydrocarbons remain in the liquid state, contacting said isoparaffins with said hydrogen fluoride in said fractionating-reforming zone until substantial reforming of the isoparaffin is effected, fractionating off normally gaseous hydrocarbons from said zone during the reforming operation as a vapor mixture with hydrogen fluoride, condensing and returning at least a portion of the vaporized hydrogen fluoride to said zone, and withdrawing said reformed gasoline boiling hydrocarbons and higher hydrocarbons in liquid phase from said zone.

11. The process of producing a relatively wide boiling mixture of high quality gasoline boiling hydrocarbons from a relatively narrow boiling fraction of gasoline boiling isoparaffins which comprises feeding said isoparaffins and hydrogen fluoride of alkylation strength to a fractionating-reforming zone, maintaining said zone under such conditions that normally gaseous hydrocarbons are vaporized while gasoline boiling hydrocarbons and higher hydrocarbons remain in the liquid state, contacting said isoparaffins with hydrogen fluoride in said zone until substantial reforming of the isoparaffins is effected, fractionating off normally gaseous hydrocarbons from said zone during the reforming operation as a vapor mixture with hydrogen fluoride, withdrawing reformed gasoline boiling hydrocarbons and higher hydrocarbons in liquid phase from said zone, fractionating said withdrawn liquid hydrocarbons to give a gasoline boiling fraction and a fraction of higher liquid hydrocarbons, passing said higher

hydrocarbons along with light isoparaffins to an alkylation zone, reacting said higher hydrocarbons and said light isoparaffins in said alkylation zone in the presence of hydrogen fluoride of alkylation strength to produce gasoline boiling isoparaffins, and passing these gasoline boiling isoparaffins to said fractionating-reforming zone.

12. The process of producing a relatively wide boiling mixture of high quality gasoline boiling hydrocarbons from a relatively narrow boiling fraction of gasoline boiling isoparaffins which comprises feeding said isoparaffins and hydrogen fluoride of alkylation strength to a fractionating-reforming zone, maintaining said zone under such conditions that normally gaseous hydrocarbons are vaporized while gasoline boiling hydrocarbons and higher hydrocarbons remain in the liquid state, contacting said isoparaffins with hydrogen fluoride in said zone until substantial reforming of the isoparaffins is effected, fractionating off normally gaseous hydrocarbons from said zone during the reforming operation as a vapor mixture with hydrogen fluoride, withdrawing a liquid mixture of reformed gasoline boiling hydrocarbons, higher hydrocarbons and hydrogen fluoride from said zone, condensing said vapor mixture and separating the condensate into a hydrocarbon layer and hydrogen fluoride layer, returning the hydrocarbon layer to the top of said fractionating-reforming zone as reflux and passing the hydrogen fluoride layer to said zone at a point near the bottom thereof, separating said withdrawn liquid mixture into a hydrocarbon phase and a hydrogen fluoride phase, fractionating said hydrocarbon phase to produce a gasoline boiling fraction and a fraction of higher boiling hydrocarbons, passing said higher hydrocarbons along with isobutane to an alkylation zone, reacting said higher hydrocarbons and said isobutane in said alkylation zone in the presence of hydrogen fluoride of alkylation strength to produce gasoline boiling isoparaffins, and passing these gasoline boiling isoparaffins to said fractionating-reforming zone.
